United States Patent [19]

Claytor et al.

[11] Patent Number: Des. 315,422

[45] Date of Patent: ** Mar. 12, 1991

[54] LENS ARRAY FOR PASSIVE INFRARED MOTION DETECTOR SYSTEMS OR THE LIKE

[75] Inventors: Ricahrd N. Claytor; Truman D. Black, both of Arlington, Tex.

[73] Assignee: Fresnel Technologies, Inc., Fort Worth, Tex.

[**] Term: 14 Years

[21] Appl. No.: 256,366

[22] Filed: Oct. 11, 1988

[52] U.S. Cl. D26/122; D10/121

[57] CLAIM

The ornamental design for a lens array for passive infrared motion detector systems or the like, as shown and described.

DESCRIPTION

The single FIGURE is a front elevational view of a lens array for passive infrared motion detector systems or the like showing our new design, the lens array being a flat, rectangular, thin sheet having a plain, smooth, rear surface with no ornamentation.
